UNITED STATES PATENT OFFICE

MELCHOR CENTENO V., OF CARACAS, VENEZUELA

TELEVISION APPARATUS

Application filed April 14, 1931. Serial No. 530,069.

The present invention relates to television systems and apparatus in general.

The primary object of the present invention is to provide a novel arrangement whereby a single light source may be used for simultaneously scanning an object and tracing an image in a two-way television system.

Another object is to provide a novel light source adapted for use in the arrangement referred to in the preceding paragraph.

A further object is to provide a novel apparatus for producing vibratory motion of the vibrable mirror used in a television system for tracing the image and scanning the object.

Other objects reside in detail improvements in apparatus used in a television system so as to secure greater reliability and simplicity of apparatus.

Various objects, advantages or features will be pointed out in the following specification and claims or will be apparent from a study thereof and of the accompanying drawings which illustrate several forms of embodiment of the invention.

In the drawings:

Fig. 1 is a front elevation of one form of embodiment of the invention.

Fig. 2 is an enlarged front view of the low frequency vibratory frame showing details of its construction and with the high frequency frame removed.

Fig. 3 is a vertical section taken substantially on the line 3—3 of Fig. 2.

Fig. 4 is an enlarged front elevation of the high frequency vibratory frame.

Fig. 5 is a vertical section taken substantially on the line 5—5 of Fig. 4.

Fig. 6 is a horizontal section taken substantially on the line 6—6 of Fig. 4.

Fig. 7 is a detail view on a large scale of the means for tightening the supporting strings of the low frequency vibratory frame.

Fig. 8 is a vertical section taken on the line 8—8 of Fig. 7.

Fig. 9 is a front elevation of a modified form which may be used.

Fig. 10 is a horizontal section taken on the line 10—10 of Fig. 9.

Fig. 11 is a large scale view in elevation of

portions of the high and low frequency vibrating frames.

Fig. 12 is a vertical section taken on the line 12—12 of Figure 11.

Fig. 13 is a detail view of a form of tightening device for the supporting wires or strings of the vibrating frames.

Fig. 14 is a vertical section taken on the line 14—14 of Fig. 13.

Fig. 15 illustrates a modified arrangement for securing the high frequency vibrations of the mirror.

Fig. 16 is a vertical section taken on the line 16—16 of Fig. 15.

Fig. 17 is a detail view showing the manner in which the vibratory member carrying the mirror is mounted on the tensioned supporting string.

Fig. 18 is a detail view of the means for tensioning the supporting string shown in Fig. 1.

Fig. 19 illustrates a further modification of the arrangement for producing high frequency vibration of the mirror.

Fig. 20 is a vertical section taken on the line 20—20 of Fig. 19.

Fig. 21 shows the manner in which the string supporting the mirror of the modification shown in Fig. 20 are attached to the low frequency vibratory frame.

Fig. 22 is a front elevation illustrating a further modification of the invention.

Fig. 23 is a section on the line 23—23 of Fig. 22 and shows the construction of the upper end of the low frequency winding or coil.

Fig. 24 is a horizontal section on the line 24—24 of Fig. 22.

Fig. 25 illustrates an arrangement whereby a single light source may be used for simultaneously scanning an object and tracing an image in a two-way television system.

Fig. 26 is an elevation of a lamp which may be used as a light source in the arrangement shown in Fig. 25.

Fig. 27 is a side elevation of the lamp shown in Fig. 26.

In Figs. 1 to 8, and Figs. 13 and 14 there is illustrated one form of embodiment of the

invention comprising a supporting frame 30 having on the inside thereof two field poles 31 which are energized by direct current so as to produce a strong magnetic field. Pivotally mounted within the field produced between the poles 31 is a coil frame 32 carrying a coil 33, the plane of the coil being parallel to the lines of force in the field. The frame 32 is suspended in a manner to permit free vibration about a vertical axis by means of a novel form of support comprising stirrups 34 attached to the sides of the coil frame and having holes 35 through which pass wires or strings 36, the free ends of the wires or strings being passed through holes in short bars 37 and these anchored by means of set screws 38. The wires 36 may be put under tension by means of thumb-screws 39 which are threaded into beveled nuts 40, the nuts 40 being prevented from turning owing to the fact that the bars 37 have turned over ears or lugs 41 between which the nuts are loosely retained. By manipulating the thumb screws 39 in suitable manner the coil frame 32 may be raised or lowered for purposes of adjustment and, when adjusted as desired set-screws 42 may be turned to lock the thumb screws 39.

Mounted within and upon the coil frame 32, with their axes transverse of the axes of poles 31, are two field coils 43 which are energized by direct current and pivotally mounted between the poles 43 is a second coil frame 44. The frame 44 supports a coil 45 and is suspended by stirrups 46 and wires 47 similar to the stirrups 34 and the wires 36 which may be adjusted or tensioned by means of an adjusting device. The adjusting device comprises a bridge 48 mounted on the frame 32 having notches over which pass the wires 47, said notches holding the wires in accurate spaced relation. Each bridge has journaled therein a shaft to which is fixed a worm wheel 49 co-operating with a worm shaft 50 journaled in the frame 32 and the ends of wires 47 are wound upon the shaft carrying the worm wheel. The shafts 50 may have a slot on one end whereby said shafts may be turned to tension of wires 47 or adjust the frame 44. Mounted within the frame 44 is a mirror 51 which is inclined slightly in the desired direction according to the position of the light source used in connection with the device.

The coils of the field poles 31 and 43 are connected to suitable binding posts DC for convenient connection to a source of direct current. The ends of coil 33 are likewise attached to binding posts LF which in practice will be connected to a source of alternating current of the order of ten cycles per second while the ends of coil 45 are connected to binding posts HF which will be connected to a source of high frequency alternating

current, say of the order of 500 cycles per second.

It will be clear that the coil frame 32 will be vibrated about its vertical axis at a rate equal to the frequency of the low frequency alternating current supplied to the coil 33 while the coil frame 44 will be vibrated about a horizontal axis at right angles to the axis of vibration of frame 32 and at a rate of vibration equal to the frequency of the high frequency current supplied to the coil 45. The consequence is that a beam of light reflected from the mirror 51 will trace an image or object several hundred times per second.

Figs. 9 to 12 illustrate a modified arrangement for securing vibration of the mirror. Similar reference characters with the subscript "b" refer to corresponding parts in Figs. 1 to 8, inclusive. The frame 30a carries field coils 31a producing a strong magnetic field therebetween within which is suspended a vibrable frame 32a by means of wires 36a and tension devices similar to the tension device shown in Figs. 13 and 14. The frame 32a carries coils 52 cooperating with the poles 31a and also field poles 43a. Vibrably mounted in the frame 32a is a frame 44a supported in the same manner as the frame 32a and carrying coils 53 similar to the coils 52. The pole pieces of the poles 31a and 43a are provided with ribs 54 coacting with similar ribs 55 formed in the pole pieces supporting the coils 52 and 53.

It will be clear that, when direct current is supplied to the poles 31a, 43a, high frequency alternating current to coils 53, and low frequency alternating current to coil 52, the mirror 51a will be vibrated in two directions at right angles to each other as in the case of the form illustrated in Figs. 1 to 8, inclusive. The purpose of the ribs 54, 55 is to insure that the vibration will commence as soon as the coils 52, 53 are energized and reduces the chances of the mirror remaining stationary as a consequence of the poles carrying coils 52 and 53 becoming co-axial with the poles 31a and 43a, that is it eliminates the possibility of the parts remaining in a dead center position and reduces the time required for the mirror to produce the required number of traces of the object or image.

Figs. 15 to 18 illustrate a further modification of the invention and show a simplified construction. The frame 32b is similar in construction and actuation to the frame 32a of the form of the invention illustrated in Figs. 9 to 12. The frame 32b carries coils 52b energized by low frequency alternating current as in the case of the coils 52 hereinbefore mentioned and also carries coils 53b energized by high frequency alternating current. Suspended between offset tips 55b of the pole pieces surrounded by coils 53b is a permanent magnet 56 carrying the mirror

51b. The magnet 56 is suspended by means of a resilient strip 57 of metal such as spring steel or brass which may be of any desired shape in section such as the flat shape shown. The ends of the strip 57 fit in suitable holes in bars 58 adjustably mounted in the frame 32b as by means of adjusting screws 59 (Fig. 18). It will be obvious that the strip 57 may be put under tension by simply turning the screws 59 by means of a suitable key inserted in the holes 60 provided for the purpose in the heads of said screws. A set screw 61 permits ready adjustment of the permanent magnet 56 longitudinally of the strip 57. It will be obvious that the permanent magnet 56 and the coils 53b energized by high frequency alternating current behave in exactly the same manner as the poles 43a and coils 53 (Figs. 9 to 12) to produce a high rate of vibration of mirror 51b in a vertical direction.

20 Figs. 19 to 21 show a modified arrangement for producing the high frequency vibration of the mirror. The frame 32c carries field poles 43c energized by direct current so as to produce a strong magnetic field. The pole pieces of the poles 43c are narrowed as shown in Figs. 19 and 20 so as to concentrate the magnetic field, and stretched within said field is a wire 62 the free ends of which are anchored to insulated blocks 63 carried by the frame 32a. The wire 62 is looped through holes in an insulated block 64 adjustably mounted in the frame 32 and passes through holes in a block 65 of insulating material. The block 65 lies between the pole pieces of poles 43c and has mounted thereon the mirror 51c. The wire 62 may be tightened by turning screws 66. When a high frequency current is passed through the wire 62 by connecting the blocks 63 to a source of such current through a suitable flexible connection the parts will function like an oscillograph vibrator element and the mirror 51c will be vibrated at a high frequency. Suitable screws 67 permit ready removal and replacement of the wire 62 whenever desired.

25 Figs. 22, 23, and 24 illustrate a further modification in which the main vibratory frame 32d carries field poles 31d and 43d energized by direct current and is suspended within a coil 33d energized by low frequency alternating current, the style of suspension from the main frame 30d being the same in construction as for the frame 32a in Fig. 9. The coil 33d is formed to fit a coil frame comprising side pieces 68 and a protective sheath 69 between said side pieces and outside of the coil. The sheath 69 is slightly enlarged and flanged at 70 to permit the supporting wires 71 from the frame 32d to pass. The side pieces 68 are flanged as at 71 to hold the coil in place while bent over lugs 72 further serve to retain the coil and its frame in assembled relation. Lugs 73 hold the side frame in place on the frame 30d. The inner vibratory

frame 44d is similar in its arrangement and mounting to the frame 44, Fig. 1 and its coil is energized by high frequency alternating current. In consequence of the energization of the coils 31d, 33d, 43d, and the coil carried by frame 44d the mirror 51d carried by said frame will vibrate continuously to produce the desired number of traces according to the frequencies selected.

30 Fig. 25 illustrates an arrangement whereby a single vibratory mirror and a single light source may be utilized to produce simultaneously the scanning of an object and tracing an image. A light source 74 is mounted at one end of a tube 75 having two branches 76, 77. Mirrors 78, 79 are mounted in such fashion that half of the light from source 74 is reflected axially of the branches 76, 77. Each branch 76, 77 has mounted therein a suitable lens system to focus a beam upon the vibratory mirror 51 which may be vibrated by any of the arrangements already described herein. A Kerr cell 80 is mounted within the straight portion of tube 75 and is arranged to vary the intensity of illumination of the beam 81 received from the light source and according to variations in the current received from the out-put side of the amplifier unit. It will be clear, that the reflected beams 82, 83 will be directed differently owing to the different angles of incidence of the two beams reflected from mirrors 78, 79, consequently an image may be traced independently of the simultaneous scanning of the object.

35 Figs. 26, 27 illustrate a novel form of light source comprising an incandescent lamp having an evacuated globe 84 attached to threaded base 85 and containing a filament 86 which preferably consists of a closely wound straight coil of wire of tungsten or metal of like light producing properties when heated to incandescence by passage of an electric current. The coil 86 is supported by rigid wires 87 which also serve as current conductors and is arranged with its axis at right angles to the axis of symmetry of the base and globe. Mounted upon rigid wires 88 is a cylindrical reflector 89, preferably of the parabolic type, and arranged so that the axis of the filament 86 will be in the focal line of the parabolic mirror. It will be obvious that such a light source will reflect a substantially rectangular beam of light.

40 The present invention may be modified as to details and arrangement, therefore, it is not desired to limit its scope to the precise embodiments herein described as they are purely illustrative of the manner in which the invention will be used in practice. In the specification and claims the terms high and low frequency current is not to be construed as restricted to mean alternating current as a periodically pulsating electric current may be used as well. Nor is the term "Kerr cell" to be construed as limited to the

particular type of means shown for varying the intensity of light as it is intended to cover all equivalents of a Kerr cell or so-called Karolus cell.

5. What is claimed is:

1. In combination, a member provided with means for producing a fixed magnetic field, a member suspended in said field and itself having means for producing a fixed magnetic field transverse to the first magnetic field, said member being mounted for vibration on the axis of its own fixed magnetic field, a mirror carrying member mounted in the second member for vibration around an axis at angles to the axis of the latter, and means for producing alternate magnetic fields of different frequencies in said second member and said mirror carrying member. 75
2. In combination, a base, means mounted thereon for producing a constant magnetic field, a member pivotally mounted in said magnetic field and carrying a low frequency coil and having means for producing a magnetic field at an angle to the first magnetic field, and a mirror carrying member pivotally mounted in the first said member in the field of the latter and having a high frequency coil, whereby the two members are vibrated in different planes and at different rates of vibration. 80
3. In combination, a base, oppositely disposed coils mounted on said base to provide a constant magnetic field, a frame pivotally mounted on the base in said field, oppositely disposed coils mounted on said frame to provide a magnetic field disposed in a plane at an angle to the first magnetic field, a low frequency coil surrounding said frame to vibrate the latter in the first magnetic field, and a mirror carrying member pivotally mounted in said frame to vibrate in a plane at right angles to the latter and having a high frequency coil to vibrate it in the field of the coils carried by said frame. 85
4. In combination, a supporting frame, field producing coils mounted on the opposite sides of said supporting frame, a vibratory frame carrying a low frequency coil mounted in the field of the coils of said supporting frame, field producing coils mounted on opposite sides of the vibratory frame to produce a magnetic field at an angle to that produced by the coils of the supporting frame, and a mirror carrying member mounted in the vibratory frame for vibration in a plane at right angles to the plane of vibration of said frame and carrying a high frequency coil in the field of the coils mounted on the vibratory frame. 90
5. In combination, a frame provided with means for producing a constant magnetic field, a second frame mounted for vibratory movement in the first said frame in the field of the latter and carrying a coil for energization by an alternating current, means for producing a constant magnetic field across the second frame at an angle to the field of the supporting frame and in the direction of the axis of vibration of the second frame, and a mirror carrying member mounted in said second frame for vibration on an axis at right angles to the axis of the vibration of said second frame, said mirror carrying member being provided with a coil for energization by an alternating current of a different frequency from that by which the coil of the second said frame is energized. 95
6. In combination, a frame provided with means for producing a constant magnetic field thereacross, a second frame mounted in the first frame for vibration around an axis at an angle to said magnetic field, and a mirror carrying member mounted in said second frame for vibration around an axis at an angle to the axis of vibration of said second frame, the latter having means for producing a constant magnetic field in the direction of the axis of vibration of the second frame, the said second frame and mirror carrying member being provided with coils for energization by alternating currents to effect their vibrations in their respective magnetic fields. 100
7. In combination, a frame provided with means for producing a constant magnetic field thereacross, a second frame mounted in the first frame for vibration around an axis at an angle to said magnetic field, and a mirror carrying member mounted in said second frame for vibration around an axis at an angle to the axis of vibration of said second frame, the latter having means for producing a constant magnetic field in the direction of the axis of vibration of the second frame, the said second frame and mirror carrying member being provided with coils for energization by alternating currents of different frequencies to effect their vibration in their respective magnetic fields. 105
8. In combination, a frame provided with means for producing a constant magnetic field thereacross, a second frame disposed in the first said frame and having means for producing a constant magnetic field thereacross at right angles to the field of the first said frame, means for mounting said second frame for vibration on the axis of its own magnetic field, a mirror carrying member disposed in the second frame, and means for supporting said mirror carrying member for vibratory movement on the axis of the first magnetic field, the mirror carrying member and the second said frame being provided with coils for energization by alternating current to vibrate the second said frame and mirror carrying member on angularly related axes. 110
9. In combination, a frame provided with means for producing a constant magnetic 115

- field thereacross, a second frame disposed in the first said frame and having means for producing a constant magnetic field thereacross at right angles to the field of the first 5 said frame, means for mounting said second frame for vibration on the axis of its own magnetic field, a mirror carrying member disposed in the second frame, and means for supporting said mirror carrying member for 10 vibratory movement on the axis of the first magnetic field, the mirror carrying member and the second said frame being provided with coils for energization by alternating current to vibrate the second said frame and 15 mirror carrying member on angularly related axes, the means for supporting the second frame and mirror carrying members comprising spaced strands disposed on opposite sides of each and swinging the second said 20 frame in the first frame and the mirror carrying member in the second frame. 80
10. In combination, a frame provided with means for producing a constant magnetic field thereacross, a second frame disposed in 25 the first said frame and having means for producing a constant magnetic field thereacross at right angles to the field of the first said frame, means for mounting said second frame for vibration on the axis of its own 30 magnetic field, a mirror carrying member disposed in the second frame, and means for supporting said mirror carrying member for vibratory movement on the axis of the first magnetic field, the mirror carrying member 35 and the second said frame being provided with coils for energization by alternating current to vibrate the second said frame and mirror carrying member on angularly related axes, the means for supporting the second 40 frame and mirror carrying members comprising spaced strands disposed on opposite sides of each and swinging the second said frame in the first frame and the mirror carrying member in the second frame, and ad- 45 justable means for tensioning said strands. 95
11. In combination, a light source, a tube provided with a duality of branches and having the light source mounted at one end thereof, mirrors mounted in said tube adjacent said branches, a remotely spaced vibratory mirror towards which the axis of said branches converge, the mirrors disposed in said tube being positioned at such angles as to direct the light source on said vibratory 50 mirror at a common point and a light valve disposed in said tube between said branches. 105
12. In combination, a base, means mounted in the base for producing a constant magnetic field, a member pivotally mounted in 55 said field and having a low frequency current coil whereby said member is caused to vibrate at a low frequency, means carried by the member for producing a constant magnetic field at right angles to said first-named 60 field, a second vibrable member pivotally 110
- 65
13. In combination, a base, means mounted in the base for producing a constant magnetic field, a member pivotally mounted in 70 said field and vibrable at right angles to the axis of vibration of the latter, said member having a high frequency current coil for co-operation with the second-named means whereby to cause high frequency vibration of the second member, and a mirror carried by the second-named member. 75
- In testimony whereof I hereby affix my signature. 85
- MELCHOR CENTENO V. 90
14. In combination, a base, means mounted in the base for producing a constant magnetic field, a member pivotally mounted in 95 said field and having a low frequency current coil whereby said member is caused to vibrate at a low frequency, means carried by the member for producing a constant magnetic field at right angles to said first-named field, a second vibrable member pivotally 100
15. In combination, a base, means mounted in the base for producing a constant magnetic field, a member pivotally mounted in 105 said field and having a low frequency current coil whereby said member is caused to vibrate at a low frequency, means carried by the member for producing a constant magnetic field at right angles to said first-named field, a second vibrable member pivotally 110
16. In combination, a base, means mounted in the base for producing a constant magnetic field, a member pivotally mounted in 115 said field and having a low frequency current coil whereby said member is caused to vibrate at a low frequency, means carried by the member for producing a constant magnetic field at right angles to said first-named field, a second vibrable member pivotally 120
17. In combination, a base, means mounted in the base for producing a constant magnetic field, a member pivotally mounted in 125 said field and having a low frequency current coil whereby said member is caused to vibrate at a low frequency, means carried by the member for producing a constant magnetic field at right angles to said first-named field, a second vibrable member pivotally 130
